CAR COUPLER

William J. Metzger, East Cleveland, Ohio, assignor to National Malleable and Steel Castings Company, Cleveland, Ohio, a corporation of Ohio

Filed July 18, 1955, Ser. No. 522,535

12 Claims. (Cl. 213—100)

This invention relates to rigid-jawed type car couplers and more particularly to "lock-set" mechanism therefor.

The purpose of the lock-setting mechanism in a car coupler is to enable a trainman to place the lock of the coupler in a position whereby mated couplers can be separated without further actuation of the uncoupling mechanism. This enables uncoupling of a car, or a group of cars, without the need of holding the lock out of locking position by means of the uncoupling rod.

This invention is particularly adapted for use with a rigid-jawed coupler commonly known as the "Industrial" type Willison coupler, in which a spring compressed between the rearward end of a longitudinally movable lock and an abutment in the coupler head maintains the lock in projected or locking position. Heretofore this type of coupler has not embodied a lock-setting feature and in order to separate mated couplers the trainman has had either to go between the cars to directly actuate the lock operating lever, or to actuate the lever from the side of the car by means of an uncoupling rod. This procedure is not only inefficient and inconvenient but also gives rise to the possibility of injury because the trainman has to hold on to the lock lever or to the uncoupling rod during the switching operation in order to maintain the lock out of locking position.

The present invention eliminates the need of manually holding the lock of the coupler in retracted position during switching operations and provides a convenient and safe method of disengaging coupled couplers.

Accordingly, the primary object of the invention is to provide a simple, yet effective lock-set mechanism for a rigid-jawed type coupler.

Another object of the invention is to provide a rigid-jawed coupler of the Willison Industrial type having a lock-set feature.

A further object of the invention is to provide a lock-setting mechanism for a rigid-jawed type coupler in which novel means is provided to manually remove the lock from lock-set position, if so desired.

A still further object of the invention is to provide a rigid-jawed coupler of the Willison Industrial type having a lock-setting feature and which will couple with present rigid-jawed type couplers not having such a feature.

A more specific object of the invention is to provide a rigid-jawed coupler in which a movable lock-set member is disposed in a recess on the buffing jaw side of the coupler head and which embodies a lock-set seat adapted for abutting engagement with the lock-operating lever to maintain the lock of the coupler in retracted or unlocking position when the coupler is coupled to an opposing coupler.

Other various features and advantages of the invention will be apparent from the following description taken in conjunction with the drawings, in which:

Fig. 1 is a plan view partly in section of a coupler embodying the invention, the lock and associated lock op-

2

erating lever of the coupler being shown in locking position.

Fig. 2 is a side elevational view partly in section of the coupler shown in Fig. 1.

Fig. 3 is a fragmentary plan view, partly in section showing the lock and associated lock operating lever of the coupler held in lock-set position by the longitudinally movable lock-set member, which in turn is maintained in retracted position by the head of the opposing coupled coupler (shown in dot-dash).

Fig. 4 is a fragmentary side elevational view of the coupler shown in Fig. 3.

Fig. 5 is an enlarged fragmentary view taken along line 5—5 of Fig. 3.

Fig. 6 is a front elevational view of the lock lever.

Fig. 7 is a side elevational view of the lock lever.

Fig. 8 is an enlarged fragmentary view similar to Fig. 5 but showing the lock-set member being moved forwardly and upwardly as the lock and associated lock operating lever of the coupler move from lock-set position back to locking position.

Referring to the drawings, there is shown a rigid-jaw coupler of a well-known type having a head 10 comprising a pulling jaw 12 and buffing jaw 14. Pulling and buffing jaws 12 and 14 have diagonal front abutment surfaces 12a and 14a, respectively, for gathering and aligning an opposing similar coupler during coupling operations. Connecting the pulling and buffing jaws and arranged at an angle to the longitudinal center line of the coupler is a buffering wall 16 having a buffering face 18 on the forward side thereof. The pulling jaw of the coupler has a recess 20 to receive the complementary buffering jaw 14 of an opposing coupler. Forming one side of recess 20 on pulling jaw 12 is a pulling face 22 adapted for engagement with complementary face 23 on the buffering jaw of an opposing coupler head when coupled couplers are subjected to pulling forces.

Formed rearwardly of jaw 14 is a guiding wing 24 comprising a laterally and rearwardly extending wall 26 reinforced by transverse web 28. Wing 24 is adapted to align opposing couplers for coupling from various horizontally angled positions.

The lock 30 of the coupler is of the usual construction and comprises a vertically extending head portion 30a and a shank portion 30b extending rearwardly into cavity 32 in the coupler head. The end of the lock shank extends through an opening 33 in flange 34 which projects inwardly from the side wall of the coupler shank. Disposed between the head portion 30a and flange 34 and encircling shank portion 30b is lock spring 36. Spring 36 is assembled under a slight initial compression in the coupler head and maintains the lock in forward or locking position, as shown in Figs. 1 and 2.

The lock is operated by lock lever 38 which comprises an upper arm 40 for attachment to an uncoupling rod and a lower arm 41 extending into cavity 32 in the coupler head. Intermediate the arms 40 and 41, a pin 39 extends through opening 39a in the lever to pivotally mount the latter on the coupler head.

Lock lever arm 41 (Fig. 6) is in the form of a crank having an upper portion 41a and a lower, substantially horizontal portion 41b. Portion 41b extends through an opening 42 in the lock, thereby placing portion 41b in following relation with the lock, and is engageable with abutment surface 42a (Fig. 3) in opening 42 during pivoting of the lever to move the lock rearwardly out of locking position into an unlocking position. Arm portion 41b terminates in a downwardly extending portion 43 substantially at right angles to the remainder of the arm. The purpose of downwardly extending portion 43 will be hereinafter described.

In accordance with the invention, the side wall 44 of the coupler head is slotted on the buffing jaw side to form longitudinally extending recess 46. Recess 46 in the embodiment shown, commences, at the juncture of wall 44 with the side wall of the coupler shank and extends forwardly to the buffing jaw 14. It will be observed that recess 46 is defined in part by top and bottom surfaces 48 and 49 (Figs. 5 and 8), inner side surface 50, and rear surface 52. As can be best seen in Figs. 5 and 8, top surface 48 slopes upwardly and rearwardly, commencing substantially adjacent the forward end thereof. Buffing jaw 14 is also centrally cored out as at 54 to form a continuation of recess 46, opening as at 55 onto abutment surface 14a of the buffing jaw. Web 56 (Figs. 1, 3 and 5) extends between the top and bottom surfaces 48 and 49 of slot 46 at the forward end thereof for a purpose which will be hereinafter described.

Lock-set member 58 is reciprocably supported in recess 46 and cored out portion 54 and comprises a head portion 58a of hook-shaped configuration (Figs. 1 and 3) and a rearwardly extending body portion 58b (Figs. 1 and 5). The rearward end of body portion 58b is enlarged as at 60 and embodies forwardly facing and downwardly sloping abutment surface 62 on the underside thereof which is adapted for engagement with complementary portion 64 on the bottom surface 49 of slot 46. The lock-set member 58 is supported on the front portion of bottom surface 49 of the recess forwardly of sloping portion 64 when the lock is in either lock-releasing or lock-set position. It will also be observed that considerable clearance exists between the top and end surfaces of the lock-set member and the corresponding top and end surfaces 48 and 52 of the recess to provide for free movement of the member upon actuation thereof.

Lock-set member 58 is provided on its inner side with a generally triangularly shaped abutment lug 59. Lug 59 comprises a forwardly facing, downwardly sloping surface 59a (Figs. 5 and 8) and a rearwardly facing lock-set seat surface 59b disposed rearwardly of surface 59a. Surface 59b is adapted for opposing engagement with the lock operating lever 38 of the coupler to maintain the lock in lock-set position, as will be hereinafter described.

A feature of the invention resides in the provision of projection 68 which is disposed on the outer side of the enlarged body portion 58b of lock-set member 58 and extends through an opening 66 in the side wall 44 of the head. Projection 68 enables a trainman to manually take the lock off lock-set position, if so desired by merely applying an upward force against the projection. As can be best seen from Figs. 1 and 8, projection 68 is disposed below the reinforcing web 28 on the coupler aligning wing 24 and is so positioned on lock-set member 58 that no interference occurs between the lug and the web upon upward movement of the lock-set member during movement of the lock off lock-set position.

When a coupler embodying the invention is not coupled to an opposing coupler, the longitudinally movable lock-set member 58 may extend slightly forwardly of the front abutment surface 14a on the buffing jaw 14, as shown in Fig. 1. However, when the coupler is coupled to an opposing coupler, the lock-set member 58 engages the buffing face 18 on the opposing coupler and is moved rearwardly to a position where the forward end of the head portion 58a of the lock-set member is disposed flush with surface 14a on buffing jaw 14 of the coupler (Fig. 3) and the member stays in such position as long as the couplers remain coupled.

The operation of the lock-setting mechanism is as follows: With a pair of opposing couplers in coupled position (Fig. 3) the lock operating lever 38 of one of the couplers is actuated by raising it from its position, as shown in Figs. 1 and 2, to a position corresponding to that shown in Fig. 4. This actuation of the lever causes

arm 41 of the lever to move lock 30 rearwardly against the resistance to compression of spring 36. As lever arm 41 moves rearwardly, the lower portion 41b thereof of slidingly engages forwardly facing, sloping surface 59a on lug 59 on the lock-set member 58 and causes the lock-set member to move slightly rearwardly and to tilt upwardly in a forward direction. It will be understood that the recess 46 allows sufficient tilting of the lock-set member without interference occurring between the latter and the top surface 48 of the slot. The hooked head portion 58a of the lock-set member 58 will engage the forward side of web abutment 56 in the recess 46 to limit rearward movement of the lock-set piece during pivoting of the lock lever and movement of the lock to lock-set position.

When the outer end of arm 41 of the lock operating lever moves rearwardly to a point past the rearward extremity of surface 59a on the lock-set lug 59, the lock-set member 58 is free to drop from its tilted position 20 to a horizontal lock-setting position, with the outer end of arm 41 of the lever disposed rearwardly but adjacent to lug 59 on the lock-set member, as may be seen in Fig. 5. In this connection it will be observed from Fig. 5 that the outer end of arm 41 of the lock lever has a flat surface 70 thereon for full surface contact with rearwardly facing lock-set surface 59b on lug 59 when the lever and lock are in unlocking position.

It will be seen therefore that the abutting engagement between the outer end of arm 41 and the rearwardly facing surface 59b on the lock-set member 58 maintains the lock operating lever 38 and the lock 30 in lock-set position (Figs. 3, 4 and 5). It will also be understood that even though the compressed spring 36 is reacting against the lock and associated lock lever and consequently also against the lock-set member 58, the latter is prevented from moving forwardly because of its engagement with the buffing face 18 on the opposing coupled coupler.

The lock of one or both of a pair of coupled couplers 40 can thus be placed in lock-set its coupler unlocking or retracted position and maintained in such position without the need of manually holding on to the lock lever or uncoupling rod, whatever the case may be, during switching operations. Thus, a convenient and safe means is provided for uncoupling coupled couplers.

With the lock of at least one of the coupled couplers in unlocking or retracted position, the couplers may be readily separated and moved to uncoupled position. With the couplers uncoupled, the lock-set member 58, of course, 50 no longer engages the buffing face of the opposing coupler and therefore the lock-set member is free to be moved forwardly by the force of the compressed lock spring 36. As will be best seen from Fig. 8, upon such forward movement of the lock-set member, the forwardly facing abutment surface 62, on the underside thereof, slidingly engages the rearwardly facing, downwardly sloping complementary portion 64 on the bottom surface 49 of slot 46 which causes the lock-set member to be cammed upwardly until the outer end of arm 41 of the lock-operating lever passes beneath the lock-set abutment lug 59. The lock and associated lock lever are then free to move back to locking position after which the weight of the lock-set member 58 causes it to assume once again a substantially horizontal position. It will be seen that the 60 weight of the enlarged section 60 of the body portion of the lock-set member aids in causing the latter to assume its normal horizontal position.

If it is desired to release the lock of the coupler from lock-set position without separating the coupled couplers, the lock-set member 58 may be manually tilted upwardly by means of projection 68 thereon extending through opening 66 on the side wall 44 of the coupler head. This tilting of member 58 will, of course, cause the outer end 70 of arm 41 on the lock lever to pass beneath the abutment

lug 59 on the lock-set member and thus the lock and associated lever will move back to a locking position in a manner similar to that as aforescribed.

It will be seen from Figs. 2, 5 and 8 that the downwardly curved portion 43 at the outer end of arm 41 of the lock lever 38 (Figs. 6 and 7) maintains the lock-set member 58 in proper position in slot 46 in the coupler head by providing a lateral support therefor. Portion 43 thereby prevents the lock-set member from becoming cocked in the slot and jamming the operating mechanism. Portion 43 of the lever also overlaps the adjacent portion of the lock shank 30b (Figs. 2 and 4) and ensures that the lever and lock will not inadvertently become disassembled as wear occurs between the various parts of the coupler.

The coupler is assembled by first inserting the lock-set member 58 into the cavity 32 in the coupler head and then feeding the hooked head portion 58a through the cored-out portion 54 in the buffering jaw, after which the member is rotated into proper position in slot 46 in the coupler head. The other parts of the coupler are then inserted in the usual manner to complete the assembly.

It will be seen that a coupler embodying the invention will easily couple with other similar types of couplers not embodying the invention and that the novel lock-setting mechanism does not interfere in any manner with the operation of the coupler.

From the foregoing description and accompanying drawings it will be readily understood that the invention provides novel lock-set mechanism for a rigid-jawed type coupler comprising a movable lock-set member that is adapted for tilting movement in a recess in the coupler head, said member having a lock-set seat thereon which engages a portion of the lock operating lever to thereby maintain the lock of the coupler in retracted or lock-set position, when the coupler is coupled to an opposing coupler. It will also be understood that when the coupled couplers are separated, the lock of the coupler is moved from lock-set position to locking position without any actuation of the operating mechanism and therefore is automatically in proper position for further coupling operations.

The terms and expressions which have been employed are used as terms of description and not of limitation and there is no intention of excluding such equivalents of the invention described or of the portions thereof as fall within the purview of the claims.

I claim:

1. In a rigid-jawed car coupler having a head, said head comprising a side wall disposed rearwardly of one of said jaws, a lock slidably mounted in said head adjacent said wall, a lever pivotally mounted on said head and interconnected with said lock for moving the latter rearwardly to an unlocking position, said wall having a generally longitudinally extending slot on the inner side thereof, said slot continuing forwardly through the associated jaw, and a reciprocable lock-set member disposed in said slot, said member being movable by said lever to lock-set position simultaneously upon actuation of the lever to move the lock to unlocking position, said member in said lock-set position being in abutting engagement with said lever to maintain the lock in said unlocking position and the forward end of said member extending through the slot in said jaw for engagement with an opposing similar coupler when the couplers are intercoupled.

2. In a car coupler having a head, said head comprising a pair of transversely spaced rigid-jaws adapted to interengage with the jaws of an opposing coupler, said head comprising a side wall disposed rearwardly of one of said jaws, a movable lock disposed adjacent said wall, a lever mounted on said head and interconnected with said lock for moving the lock to an unlocking position, said wall having a generally longitudinally extending slot on the inner side thereof, said slot ex-

tending forwardly through the associated jaw, and a lock-set member movable in said slot, said member having a laterally extending lug thereon comprising a rearwardly facing lock-set seat, said lever having a forwardly facing abutment surface thereon, said member being movable by said lever to operative position in which abutting engagement occurs between said seat and said surface for holding said lock in said unlocking position, the forward end of said member extending through the slot in said jaw for engagement with a similar opposing coupler when the couplers are intercoupled, to hold the members in said operative position.

3. In a rigid-jawed car coupler having a head, said head comprising a side wall, a lock in said head adjacent said wall, resilient means for maintaining said lock in forward locking position, a lever pivotally mounted on said head, said lever comprising a lower arm interconnected with said lock for moving the latter rearwardly to an unlocking position, said wall having a generally longitudinally extending slot therein, and movable lock-set means disposed in said slot for abutting engagement with said lever arm to maintain said lock in unlocking position, said arm having a downwardly extending portion adjacent said lock-set means to provide lateral support for the latter in said slot.

4. In a car coupler comprising a head, a buffering jaw and a pulling jaw on said head, a side wall extending rearwardly from said buffering jaw, said buffering jaw having a generally longitudinally extending opening therein, said side wall having a generally longitudinally extending slot on the inner side thereof forming a continuation of said opening, a web joining the top and bottom surfaces of said slot substantially adjacent the forward ends thereof, a movable lock-set member disposed in said slot and said opening, said member comprising a hook-shaped head portion engageable with the front surface of said web to limit the rearward movement of said member during movement of the associated coupler lock to lock-set position, an opening in said side wall, and a projection on said member extending through said last-mentioned opening, said projection providing handle means for manually moving said member to inoperative position.

5. A lock-set member for a car coupler of the rigid-jawed type comprising a head portion and a body portion, said head portion being of hook-shaped configuration and said body portion being enlarged adjacent its rearward end, said enlarged end comprising a forwardly facing rearwardly sloping cam surface adapted to engage a complementary surface in a coupler to cause the member to move to a forwardly tilted position during movement of the lock of the coupler from lock-set to locking position.

6. A lock-set member in accordance with claim 5 wherein said member comprises a laterally extending lug on the inner side thereof, said lug having a rearwardly facing lock-set seat thereon adapted for engagement with an associated lock operating lever.

7. A lock-set member in accordance with claim 6 comprising a laterally extending projection on the outer side thereof to provide means for manually lifting said member to said forwardly tilted position.

8. In a rigid-jawed coupler, a lock slidably mounted adjacent one of the jaws for movement between a forward locking position and a rearward unlocking position, means for urging the lock forwardly, a lock-set member reciprocably supported for movement between a forward lock-releasing position and a rearward lock-setting position, an operating lever having a portion connected with the lock in following relation therewith and adapted upon actuation of the lever to move the lock to said unlocking position, said lever having means thereon for engagement with said member to move the latter to said lock-setting position simultaneously with movement of the lock to unlocking position, said lever

portion having a surface disposed for opposingly engaging a surface of said member at said unlocking position of the lock and said lock-setting position of the member to resist forward movement of the lock.

9. In a rigid-jawed coupler, a lock slidably mounted adjacent one of the jaws for movement between a forward locking position and a rearward unlocking position, means for urging the lock forwardly, a lock-set member reciprocably supported for movement between a forward lock-releasing position and a rearward lock-setting position, an operating lever having a portion connected with the lock in following relation therewith and adapted upon actuation of the lever to move the lock to said unlocking position, said lever having means thereon for engagement with said member to move the latter to said lock-setting position simultaneously with movement of the lock to unlocking position, the lever portion having a forwardly-facing surface and said member having a rearwardly-facing surface arranged for engagement at said unlocking position of the lock and said lock-setting position of the member.

10. A car coupler comprising a head having a pair of rigid transversely spaced jaws, a lock slidably mounted adjacent one of the jaws for movement between a rearward unlocking position and a forward locking position in which it traps the jaw of another coupler between said jaws, means for urging the lock forwardly, a lock-set member reciprocably supported for movement between a forward lock-releasing position and a rearward lock-setting position, an operating lever having a portion connected with the lock in following relation therewith and adapted upon actuation of the lever to move the

5 lock to said unlocking position, said lever having means thereon for engagement with said member to move the latter to said lock-setting position simultaneously with movement of the lock to unlocking position, said lever portion having a forwardly-facing surface and said member having a rearwardly-facing surface arranged for engagement at said unlocking position of the lock and said lock-setting position of the member.

10 11. The car coupler of claim 10 comprising means for shifting the lock-set member out of engagement with the lever as the lock and said member move forwardly from respective rearward positions to their forward positions, said means comprising an upwardly inclined rearwardly-facing surface of the head in opposed engageable relation with a downwardly-facing surface of the member at the rearward position of the latter.

15 12. The car coupler of claim 8 wherein the head of the coupler has a buffering jaw, and the lock-set member is disposed adjacent the inner surface of a side wall contiguous with the buffering jaw and has a forward hook-shaped portion for engagement with the buffering jaw to limit rearward movement of the member.
